INKING MECHANISM FOR PRINTING
PRESSES AND THE LIKE

Joseph Calcaterra, Thornwood, N. Y.

Application September 28, 1937, Serial No. 166,110

7 Claims. (Cl. 101—349)

This invention relates, as indicated, to inking mechanism for printing presses and the like.

Attempts have heretofore been made, as exemplified by the patents to Ray 701,221; Gally 5 733,023 and Thomas 1,135,075 to secure a more even or uniform distribution of the ink on the form or distribution rollers of a printing press through the use of a relatively short roller having a movement similar to the movement of the 10 "vibrator" rollers in conventional printing presses. While the redistribution, in these efforts is improved as against inking mechanisms utilizing full-length vibrators, it has not been improved to the point of providing a layer of 15 ink of uniform thickness on the form rollers at each and every impression, which has been found necessary in order to preclude the possibility of "ghosts" and "patterns" being formed on the form. These "ghosts" and "patterns", as is well 20 known to those skilled in the art, result from "repeating" on the form a section of the roller from which the ink film has already been removed.

The invention, accordingly has, as its primary 25 object, the provision of inking mechanism through the use of which a much more even or uniform distribution of ink on the form rollers of a printing press or the like can be attained than can possibly be attained through the use of 30 existing inking mechanisms.

Another object of the invention is to provide 35 mechanism of the character described, through the use of which the adjustment of the press for even inking may be accomplished with the expenditure of considerably less time, effort and wastage of paper and ink than is possible with present inking mechanisms, and whereby a comparatively inexperienced pressman can adjust the press for satisfactory inking in less time and 40 with better results than can be achieved by much more experienced pressmen with present mechanism.

To the accomplishment of the foregoing and 45 related ends, I have illustrated in the accompanying drawing, the inking mechanism of my invention as employed in association with a printing press of the bed and cylinder type, such, for example as that disclosed in Honigmann Patent No. 1,774,272, although it is desired to direct attention at this point to the fact that the mechanism is susceptible with but slight modification, of being used in association with other cylinder presses, rotary, offset or platen presses, 50 proof-presses, lithographic presses, and varnishing machines.

In said annexed drawing, Fig. 1 is a plan view of a portion of the press, with parts thereof removed to more clearly show the essential features of the inking mechanism; Fig. 2 is a cross-sectional view, taken on the line 2—2 of Fig. 1; Fig. 3 is a transverse cross-sectional view of the redistributor roller, taken on the line 3—3 of Fig. 4; Fig. 4 is a longitudinal cross-sectional view of a portion of the redistributor roller, taken on the line 4—4 of Fig. 3; and Fig. 5 is a fragmentary cross-sectional view, showing the manner in which the frame links are secured to the frame.

Referring to said drawing, the press comprises 15 a delivery conveyor frame similar to the frame 230 in the aforesaid Honigmann patent, this frame being pivoted, as on a shaft 1 journalled in the brackets 2 of the delivery table, so that the frame may be swung upwardly to permit access to the inking mechanism disposed therebelow.

One of the distributor rollers 3 of the inking 20 mechanism is shown in the drawing, the balance of the inking mechanism since it is fully disclosed in the aforesaid patent, being omitted. This distributor roller is designed to receive ink 25 from a suitable source, such as an ink fountain, and to transfer such ink onto inking rollers, which, in turn, are designed to contact with the form on the bed of the press.

The delivery conveyor frame carries a set of 30 endless tapes that pass over rollers in the ends of the frame, and when the frame is in its normal operative position, the free end thereof rests upon and is temporarily secured to suitable abutments on the housings in which the ends of the 35 cylinder of the press are journalled.

The frame comprises side members 4 and 5 and a cross-member 6, secured at its ends to the rear ends of said side members. Secured to the side members 4 and 5, intermediate the ends of 40 the latter, as by cap screws 5a, which are in threaded engagement with the side members, (see Fig. 5) are links 7 and 8, which carry, at their lower ends, a cross-rod 9. The axis of this cross-rod is parallel with the axis of the distributor roller 3. By loosening the cap screws 5a, the links may be swung to any desired angular 45 position with respect to the plane of the frame, to thereby vary the pressure or contact between the redistributor roller to be presently described 50 and the distributor roller 3, without affecting the balance of the mechanism.

Mounted on and spaced somewhat from the cross-rod 9, as by bushings 10 brazed or otherwise secured to the ends thereof, is a hollow shaft 55

11. Mounted for rotation about this shaft is a short roller 13, which I term a "redistributor" roller. This roller is provided with internal bushings 12 at the ends thereof to facilitate rotation 5 of the roller about the shaft 11. The roller 13 is maintained against endwise movement on the shaft 11 by means of collars 12a and 12b which are secured to the shaft 11 as by set screws 12c. These collars are of somewhat smaller external 10 diameter than the roller 13, so as to avoid engagement of the collars with the roller 3 when the roller 13 is reciprocated, as will be presently described. The collar 12b is provided with radially extending lugs or ears 14, which are apertured 15 to receive a pivot pin 15. The roller 13 is less than half, and preferably about one-third, the length of the distributor roller 3, and in cases where the roller 3 is a metallic roller, the roller 13 is preferably a composition roller. In cases 20 where the roller 3 is a composition roller, the roller 13 is preferably a metallic roller.

The roller 13 is thus free to rotate about the shaft 11, being rotated by the roller 3 due to its frictional contact or engagement with the latter. 25 At the same time that it is thus rotated, the roller 13 is positively reciprocated along the entire length of the roller 3 as a result of reciprocal movement of the hollow shaft 11. Reciprocal movement of the shaft 11 is accomplished by 30 means of mechanism which will now be described.

The shaft 1, which carries and drives the rollers over which the delivery tapes run, is driven by the main shaft 16 of the press through the 35 medium of a sprocket chain 17 and sprocket 18, the sprocket being keyed to the shaft 1. The shaft 1 extends beyond the side 4 of the delivery frame and has keyed to the end thereof a second sprocket 19. Sprocket 19, through the medium of sprocket chain 20 drives a second sprocket 21. Sprocket 21 is keyed to a stub shaft 22 journalled in a bracket 23 carried by the side member 4 of the frame. The stub shaft 22 has secured to its inner end a spur gear 24, which, 40 through the medium of spur gear idler 25, drives a spur gear 26. Spur gear 26 is secured to the outer end of a stub shaft 27 which is carried by the side frame member 4. The shaft 27 has keyed to its inner end a worm 28 which is in 45 mesh with and drives a worm gear 29. The worm gear 29 is journalled for rotation about a vertical pin 30 mounted in a housing 31 extending from the side member 4 of the frame.

The worm gear 29 is provided with an eccentric pin 32 to which is pivotally secured one 50 end of a pitman 33. The other end of this pitman is pivotally secured as by a pin 34 to a lever 35. The lever 35 is pivotally secured as by a pin 36 to the cross-member 8 of the frame 55 at a point intermediate the ends of the latter, and is pivotally secured as by a pin 37 to one end of a link 38. The other end of the link 38 is pivotally secured to the pin 15.

It may be noted, at this point, that the elements 50 to 38 inclusive, as well as the elements 6 and 9 to 15 inclusive, are all in planes below the delivery frame proper, so that none of these elements interfere in any way with the operation of the delivery tapes.

70 It may also be noted that the redistributor roller 13, as the result of operation of the foregoing mechanism, is positively reciprocated along the rod 9, between the positions indicated in solid and dot and dash lines in Fig. 1, and that 75 this reciprocal movement of the roller is applied

to the roller along lines which are parallel or substantially parallel with the axis of the rod 9, thereby eliminating any tendency of this rod to bend, as the roller reciprocates. Consequently, the pressure of the roller 13 on the roller 3 is more or less constant throughout the major portion of the movement of the roller 13.

It may be further noted that since the main shaft 16 from which substantially all of the operative parts of the press are driven, is driven throughout the operation of the press, the roller 13 will be continuously rotated by the roller 3 and positively and continuously reciprocated along the latter, throughout the entire period of operation of the press, i. e., throughout the printing operations.

Due to the fact that the roller 13 is a short roller, less than half the length of the roller 3, and is continuously rotated and positively and continuously reciprocated throughout the operation of the press, an even or uniform redistribution of the ink on the form rollers is secured. As a matter of fact, a layer of ink of substantially uniform thickness is formed on the form rollers and the possibility of "ghosts" and "patterns" being formed on the form thereby precluded. Moreover, the adjustment of the press for even inking may be accomplished with the expenditure of considerably less time, effort, and wastage of paper and ink than is possible with present inking mechanisms, so that a comparatively inexperienced pressman can adjust the press for satisfactory inking in less time and with better results than can be achieved by much more experienced pressmen with present mechanisms, especially in cases where a complex form of heavy solids and light face type are unevenly distributed over the surface of the printing form.

The reciprocation of the redistributor roller is independent of the rotation of the distributor 40 roller or other rollers of the distributor roller assembly. Moreover, while it has been found desirable to so proportion the various parts of the mechanism as to cause one complete reciprocation of the redistributor roller for every press 45 impression, in order to obtain a complete redistribution of the ink in the roller for every impression, uniform, satisfactory printing results may be obtained even when there is but one complete reciprocation of the redistributor roller for 50 every three or four impressions, and this, in spite of rough adjustment of the fountain or the difficulties imposed by irregular or complex printing forms. The number of reciprocations for every 55 press impression can be changed very easily, by simply changing the ratio of the gear train consisting of the gears 24, 25 and 26, or the number of teeth in the worm gear 29.

In cases where the distributor rollers are more than about 15 inches long, it is desirable to use 60 more than one redistributor roller, the redistributor rollers in that event being spaced apart or timed so that they contact different sections along the length of the distributor roller at any given point of the operating cycle. Moreover, 65 some increase in redistributor efficiency may be gained by using one or more redistributor rollers in association with more than one of the regular distributor rollers.

Other methods of reciprocating the redistributor roller may be employed than the one described. Moreover, the redistributor may be used in association with other rollers in the ink roller assembly, and may be used in association with the inking mechanism of other cylinder presses. 75

5 rotary, offset or platen presses, proof-presses, lithographic presses and varnishing machines. The invention also is adapted for use in redistributing other substances than ink, such as paint, gum, etc.

10 Other modes of applying the principle of my invention may be employed instead of the one explained, change being made as regards the mechanism herein disclosed, provided the means stated by any of the following claims or the equivalent of such stated means be employed.

I, therefore, particularly point out and distinctly claim as my invention:

15 1. In an inking mechanism for printing presses and the like, the combination of a distributor roller, a redistributor roller in rolling contact therewith, said redistributor roller being less than half the length of said distributor roller, and means for positively and continuously reciprocating said redistributor roller along substantially the entire length of said distributor roller throughout the 20 operation of said press and at least once for four impressions of the press.

25 2. In an inking mechanism for printing presses and the like, the combination of a distributor roller, a redistributor roller in rolling contact therewith, said redistributor roller being less than half the length of said distributor roller, and means for positively and continuously reciprocating said redistributor roller along substantially the entire length of said distributor roller throughout the 30 operation of said press, said redistributor roller being in constant contact with the distributor roller throughout said reciprocating movement.

35 3. In an inking mechanism for printing presses and the like, the combination of a distributor roller, a redistributor roller in rolling contact therewith, said redistributor roller being less than half the length of said distributor roller, and 40 means for positively and continuously reciprocating said redistributor roller along substantially the entire length of said distributor roller throughout the operation of said press and at least once for four impressions of the press, the 45 reciprocating forces being applied substantially in line with the axis of the redistributor roller throughout the reciprocations thereof.

50 4. In a fluid distributing mechanism, the combination of a surface adapted to be coated with said fluid, a redistributor roller in contact with said surface, and means for reciprocating said roller transversely of said surface in such a man-

5 ner as to cause any predetermined point on said roller to traverse more than half the width of said surface in each direction during each reciprocating stroke, said reciprocations being at the rate of at least one for every four cycles of operation of the unit with which the mechanism is associated.

10 5. In a fluid distributing mechanism, the combination of a fluid distributing roller, a redistributor roller in rolling contact therewith, and means for reciprocating said redistributor roller along said distributor roller in such a manner as to cause any predetermined point on said redistributor roller to traverse more than half the length of said distributor roller in each direction 15 during each reciprocating stroke, said reciprocations being at the rate of at least one for every four cycles of operation of the unit with which the mechanism is associated.

15 6. In an inking or fluid distributing mechanism 20 for printing presses and the like, the combination of a rotatable distributor roller, a redistributor roller in rolling contact therewith, said redistributor roller being less than half the length of said distributor roller and arranged with its axis substantially parallel with the axis of the latter, and means for positively and continuously reciprocating said redistributor roller along substantially the entire length of said distributor roller throughout the operation of said press and at 30 least once for every ten press impressions, said redistributor roller being in constant contact with the distributor roller throughout said reciprocating movement.

25 7. In an inking or fluid distributing mechanism 35 for printing presses and the like, the combination of a rotatable distributor roller, a redistributor roller in rolling contact therewith, and means for positively and continuously reciprocating said redistributor roller along said distributor roller in such a manner as to cause any point on said redistributor roller to move more than half the length of said distributor roller in each direction 40 during each reciprocation, said means including mechanism for effecting at least one complete reciprocatory movement of the redistributor roller for every ten press impressions, and said redistributor roller being arranged with its axis substantially parallel with the axis of the distributor roller and being in constant contact with the latter throughout said reciprocating movement.

45 50 JOSEPH CALCATERRA.
